INVENTOR
WILFRED C. COOK
BY
Frank D. Dwyer
ATTORNEY

UNITED STATES PATENT OFFICE.

WILFRED C. COOK, OF FRESNO, CALIFORNIA.

PISTON-RING COMPRESSOR.

Application filed March 15, 1922. Serial No. 543,962.

To all whom it may concern:

Be it known that I, WILFRED C. COOK, a citizen of the United States, and resident of Fresno, in the county of Fresno and State of California, have invented certain new and useful Improvements in Piston-Ring Compressors, of which the following is a specification.

My invention relates to a device for use when installing rings in explosion engines and the like and is designed for use to compress the ring while the piston is being positioned within its respective cylinder, and has for its object the providing of a device for the above purpose which will be simple in construction and operation, and which can be easily and quickly adjusted to compress the ring from any convenient position.

Other objects and advantages will appear hereinafter and, while I have shown and will describe the preferred form of my invention it will be understood that I do not limit myself to such preferred form but that various changes and adaptations may be made therein without departing from the spirit of my invention.

In the drawings accompanying and forming a part hereof:

Fig. 1 is a side elevation of my device ready for use.

Fig. 2 is a top plan of Fig. 1.

Fig. 3 is a side elevation of Fig. 1.

Fig. 4 is an enlarged fragmentary detail of a portion of my device.

Figs. 5 and 6 are fragmentary details of a portion of my device.

Referring to the drawings my device comprises a pair of handles 7 pivotally connected together intermediate their ends to form a pair of pliers. The upper ends or noses of these pliers are provided with apertures 8, and each aperture 8 has a portion cut away at the center of its uppermost edge to form a recess 9, the whole forming a substantially T-shaped recess as best shown in Fig. 4. Mounted in one of the recesses 8 in each nose is a free end 10 of the ring holder 11 which holder is in the form of a ring of wire or the like and is of a size such that when compressed it will tightly hold the ring within its respective groove of the piston and flush with the outer wall of the piston. The free ends 10 of the ring holder 11 terminate in a

semi-circular portion of a size and configuration to fit within the recesses 8 and 9 and are offset so that the body of said holder will lie in a plane slightly above the edge of the nose of the pliers.

In the operation of my device the ring will first be positioned within its groove in the piston. The ring holder will then be positioned to surround said ring.

The pliers will then be operated, by moving the handles together, to compress the ring holder and with it the ring.

The piston will then be moved until the ring is within the cylinder when the pliers will be released and the ring holder removed. This process will be repeated until all the rings are positioned.

As shown in the drawings my device is being used with the ring holder at a right angle to the pliers, but in the event it is desired to use the same in a position parallel with the pliers the ends of the ring holder will be positioned in the recesses 9.

Having described my invention what I claim is:

1. In a ring compressor the combination with a pair of movable jaw members having substantially opposed T-shaped openings in the free ends of said jaws, of an annulus having the free ends thereof bent to extend at a right angle to the body portion and then bent to form hooks lying in a plane parallel with said body portion and adapted for engagement with the T-shaped opening in the jaw members, substantially as and for the purpose described.

2. A ring compressor comprising an annulus adapted to be positioned to surround said ring, said annulus having its free ends bent to extend at right angles to the body portion of said annulus and then bent to form hooks lying in a plane parallel with said body portion; and means adapted to engage said hooks to draw said free ends together.

3. A ring compressor comprising an annulus adapted to be positioned to surround said ring, said annulus having its free ends bent to extend at right angles to the body portion of said annulus and then bent to form hooks lying in a plane parallel with said body portion; in combination with a pair of pliers having substantially opposed T-shaped recesses in the free ends of the jaws thereof adapted to receive

the hook ends of said annulus, said hooks and recesses being so constructed and arranged that the body portion of said annulus will lie in a plane without the plane 5 of said pliers.

4. A ring compressor comprising in combination a pair of pliers provided with opposed substantially T-shaped openings in the ends of the noses thereof, and a ring 10 holding member formed in the shape of a ring, having its free ends offset and terminating in hooks adapted to be mounted in said openings, said hooks and openings being so formed that when positioned for 15 use the body portion of said ring will lie in a plane without the plane of said pliers.

5. A ring compressor comprising a pair of tongs provided with a plurality of communicating recesses in the ends of each of the jaws thereof; an annulus adapted to be positioned to surround said ring, said annulus having its free ends terminating in hooks adapted to be positioned within opposed pairs of said recesses, the hook portions of said annulus being offset whereby 20 when positioned for use said annulus will lie in a plane outside the plane of said tongs. 25

In witness that I claim the foregoing I have hereunto subscribed my name this 20 22nd day of December 1921.

WILFRED C. COOK.
